[73] Assignee: **Hitachi Medical Co., Ltd., Tokyo, Japan**

[57] **CLAIM**

The ornamental design for a magnetic resonance imaging scanner, as shown.

[**] Term: **14 Years**

DESCRIPTION

[21] Appl. No.: **501,501**

FIG. 1 is a front, top and right-side perspective view of a magnetic resonance imaging scanner showing our new design;

[22] Filed: **Mar. 21, 1990**

FIG. 2 is a front elevational view thereof;

[52] U.S. Cl. **D24/158**

FIG. 3 is a right side elevational view thereof, the left side elevational view being identical thereto;

[58] Field of Search **D24/158, 159; 324/300-314, 318, 319, 322-324; 378/4-27**

FIG. 4 is a top plan view thereof;

[56] **References Cited**

FIG. 5 is a rear elevational view thereof; and,

U.S. PATENT DOCUMENTS

FIG. 6 is a bottom plan view thereof.

D. 270,182 8/1983 Wagner **D24/159**
